 France, a French corporation

Application December 2, 1946, Serial No. 713,406
 In France December 20, 1945

5 Claims. (Cl. 178—70)

1

My invention relates to high speed telegraphy using codes of the arhythmic type, and in particular, to means for correcting for line distortion of signal elements, especially their characteristic instants of current reversal.

It is well known, in telesignalling, that the incoming signals, telegraph for example, are deformed with respect to the signals transmitted. This distortion, which depends on the propagation constants of the line, takes the form of a lengthening or a shortening of the signals. In other words, the distribution in time of the characteristics defined by the periods of change of polarity, in the case of operation using double current, is not identical at the sending end and at the receiving end. Moreover, to the distortion of the line there may be added the distortion caused by the transmitter itself.

In order to remedy this disadvantage which may have as a consequence certain errors or omissions in translation, several arrangements have been proposed. These arrangements are, in general, mechanical solutions, the cost of which is high, and which require delicate operating and maintenance apparatus.

A new and particularly simple solution has been described by Pierre, in his patent application Ser. No. 592,770, filed May 9, 1945. It permits of reducing theoretically to zero and practically to a very small percentage, the distortion of telegraph signals transmitted in an arhythmic or start-stop code, up to agreement with a ratio of distortion of 50%.

In the drawings:

Fig. 1a shows for a typical character the component signal elements constituting a train, in a representative high speed arhythmic code, as applied by a transmitter at the sending end of a telegraph transmission line;

Fig. 1b shows the received signal train of Fig. 1a after it has been distorted in transmission over a line;

Fig. 1c shows after correction a signal wave train which has been distorted corrected according to a particular method of reversing current polarity; and

Fig. 2 is a circuit diagram of the system of the present invention for correcting line distortion and re-transmitting the corrected signal.

The explanation of the phenomena in the case

2

of a signal transmitted in the arhythmic or start-stop code is as follows: the line is always traversed by a current. This current is positive in the absence of signal modulation. Each character (letter, cipher, punctuation, and so on) is composed of five signal elements called code signals. These signal elements are preceded by a "Start" signal element (negative polarity) and followed by a "Stop" signal element. Figure 1a annexed shows the diagram of a train of signals corresponding to any character taken by way of example.

The receiving relay, which is traversed by positive current in the absence of signal modulation, 15 is traversed by a negative current during the Start signal, then by positive or negative currents during the code signals, the order and the duration of these signal elements depending on the character sent, and finally, by a positive current 20 during the Stop signal. This latter polarity is maintained until the following train of signal elements of the next character.

The duration of each of the elementary signals is, in the system of practical operation in use on 25 the French telegraph network, 20 milliseconds. The Stop signal may last indefinitely in the absence of signal modulation.

The distortion has for its effect to extend or shorten the signal elements (Start, Code or Stop 30 signals). In other words, if there is taken as zero time the period of passage from the Stop to the Start, the characteristic instants (instants of reversal of current) which, in the case of perfect signal modulation, would have taken place in 35 times of 20—40—80—100 and 120 milliseconds, are advanced or retarded by amounts which depend both on the sending device and on the constant of propagation of the line. Figure 1b represents the wave shape after deformation by distortion 40 in transmission over a line, of the train of signals the perfect signal modulation of which is shown in Figure 1a.

The method forming the subject of the above-mentioned invention of Pierre consists in retarding 45 by one half the duration of an elementary signal, that is to say by 10 milliseconds, the characteristic instants of the corrected signal. For this purpose, assuming as origin the reversal Stop-Start times, the times 10—30, —50—60—70—90— 50 110 and 130 milliseconds are noted. These times

are the characteristic instants of the corrected signals. The polarity which follows each new characteristic instant is the polarity of the signal received at the period of this new characteristic instant.

Figure 1c shows the application of this principle to the correction of the distortion which affected the signals represented in Figure 1b.

It is seen that under these conditions the distortion correction may reach 50% on the sole condition that the noting of the time 10-30-50... milliseconds is made in precise manner.

The present invention has for object to provide a device for its carrying out the method which has just been explained.

It is characterised by the use, for the noting of the times, of an oscillating relaxation tube the output plate current of which is composed of a series of very short impulses spaced apart by the duration of an elementary signal of the code used.

The operation of this relaxation tube is triggered by the reception of a Start signal, a member such as a relay always providing a certain delay between the appearance of the Stop-Start reversal signal element and the sending of the first short pulse. This delay is, preferably, equal to one half of the duration of an elementary signal of the code employed.

A second oscillating relaxation tube delivers an output plate current constituted by a series of short pulses spaced apart by the total duration of a character.

This second relaxation tube is synchronized by the first tube, its first pulse coinciding with the first pulse of this latter. It produces, by its second pulse which is triggered at the end of the last Start signal element of the character received, the return of the correcting circuits to the initial state.

Figure 2 represents a construction of the system forming the subject of the present invention applied to a system operated according to a Start-Stop code in which each character is composed of five elementary signals (plus a Start signal), each of these signal elements lasting 20 milliseconds. The contact representing the rest or de-energized position of the tongue or armature of each relay is designated R, and the contact representing its energized position is designated T.

In this figure 2E represents the input terminals of the signal modulation to be corrected as received on an incoming line and S represents the output terminals of the corrected modulation as delivered from the two output controlled contacts of output relay REL-3 to which two contacts the opposite polarities of the output line voltage are applied as applied to the out-going line.

The relay 1 is the starting relay and has two windings. During the Stop signal element this relay 1 is at rest in the position R on its contact 11; its first winding can be traversed only by the negative telegraph currents, by reason of the presence in its circuit of the rectifying element of unilateral conductivity red; on the other hand, its second winding is traversed by the plate current of the tube L2, which is then zero, since the cathodes of the tubes L1 and L2 are not grounded when the relay REL-1 is on its rest contact R or 11.

The relay 2 is the end relay and has three windings. Its three tongues are normally in the position R (rest) on contacts 22, 24, 26 except during the duration of the second pulse of the oscillat-

ing relaxation tube L2. The function of these contacts of relay 2 is to bring to an initial defined state the potential of the condensers C1, C2 and C3, and the electromagnetic energy contained in the relay 1. The precision of the determination of the characteristic instants of the corrected signal element depends on the reactive energy of the circuit elements which determine the frequency of the oscillators. It is important that at the moment of Stop-Start reversal, this energy may be perfectly defined.

The relay 3 which has two windings is responsive to the pulses of the plate current of the tube L1 (20 milliseconds oscillator). The pulses throw the tongue of the relay 3, either to the left to contact 31, or to the right to contact 32, according to the position of the armature of relay 4, which follows the variations of the applied signal received at input terminals E. Relays 3 and 4 are usual types of telegraph relays with polarized armatures, and when their armatures have been actuated against one contact by a current applying a magnetic field in a certain direction, they retain that position until an opposing field is produced by a current in the opposite direction which traverses the proper winding. Only one winding of relay 3 is energized at a time, the current in a given one of its windings does not reverse. Current flows in one or the other of the windings of relay 3 to throw its armature one way or the other. Current may flow in either direction through the winding of the relay 4. The line sending battery M applies to the output terminal S either a positive line potential through contact 31 or a negative line potential through contact 32.

The tube L1 is the oscillating relaxation tube of period 20 milliseconds. The frequency of this oscillation is determined by the circuit Z2 C2.

An external synchronization may be applied to this tube through the medium of the transformer X3 as from a source 61 supplying 50 cycle alternating current. The source of synchronization may, moreover, be common to a large number of correcting devices.

The tube L2 is the oscillating relaxation tube of 120 milliseconds period. The frequency of this oscillation is determined by the circuit Z3 C3. The release of the top produced by the tube L2 is synchronised with the release of the sixth top of the tube L1 due to the transformer X4.

The apparatus operates in the following manner. 10 milliseconds after the Stop-Start reversal, the relay 1 starts operating; the cathodes of the tubes L1 and L2 are re-connected to earth; the tube L1, the circuits of which have been designed for this purpose, mark the times 10-30-50-70-90-110 and 130 milliseconds, by short current pulses in its plate circuit. These pulses give the characteristic instants of the corrected signal modulation. The tube L2, the circuits of which have been designed for this purpose, mark the times 10 and 130 milliseconds by the short current pulses in its plate circuit.

The first pulse furnished by L2, triggered at time $t_0=10$ milliseconds, has no effect on the behavior of the relays 1 and 2, while the second pulse triggered at time $t_1=130$ milliseconds, brings the tongue of 1 back to its position of rest, and during a very short time brings the tongues of the relay 2 to their actuated or "working" position. This last operation produces the discharge of the condensers C1, C2 and C3, as also the interruption of current in the winding 1 of the relay 1. Immediately after the end of the pulse of

the tube 2, the circuits return to their initial state, and are ready to effect a new correction, the commencement of which will be controlled by a Stop-Start reversal.

The operating cycle for one given complete start-stop signal is as follows:

Time:

Rest position.—Signal stop:

Positive polarity on the right terminal E.

The winding 1 of relay 1 is not energized because of the presence of the rectifier. Its winding 2 is not energized since the circuit of the tube L2 is open because of the release of relay 1.

The relay 1, therefore, remains in rest position.

The winding 1 of the relay 2 is permanently energized, and tends to place the armature of this relay in the rest position, its winding 2 is energized by the current of the stop signal and its action is opposed to that of the winding 1, but the flux of winding 2 is smaller than that of winding 1. Furthermore, the winding 3 is not energized since the circuit of the tube L2 is open to ground because of the rest position of relay 1.

The relay 2 remains at rest.

The relay 4 is energized in the sense corresponding to the positive impulses and it directs the +A voltage toward one of the windings of relay 3 (1 for example). However, this winding is not energized, since the tube L1 does not deliver output but the armature of relay 3 stays, however, on its contact +T, where it has been placed at the beginning of the stop signal, and a positive polarity is sent and applied to the right terminal X.

Time:

Zero.—Beginning of the start signal.—The polarity of the right terminal E becomes negative:

The winding 1 of relay 1 is energized but relay 1 remains at rest because of its delayed operation. The winding 2 of the relay 1 is not excited, its circuit being opened by the rest contact of relay 1.

The winding 2 of relay 2 is energized in the sense inverse to the preceding sense and its flux reinforces that of winding 1, to maintain the armature at rest, the winding 3 is not energized.

The relay 2 remains at rest.

The relay 4 is energized in the opposite sense from the preceding sense; it puts into the circuit the winding 2 of the relay 3, but this winding is not yet energized since the circuit of the tube L1 is opened by the rest position of relay 1. The armature of the relay 3, therefore, does not budge and a continuous positive polarity has been applied to the terminal S.

10 milliseconds.—Midpoint of the start signal:

The delay action period of relay 1 having expired, the relay 1 comes into operative position. It closes a circuit of the tubes L1 and L2 which produce a very short pulse. The winding 2 of relay 1 is energized during the duration of the short pulse, which has no effect on relay 1, the ampere turns of the winding 1 being preponderant.

The winding 3 of the relay 2 is energized during the duration of the short pulse, which tends to hold its armature in operative position, but the ampere turns of this winding are smaller than the sum of the ampere turns of the windings 1 and 2, so that the relay 2 remains in unoperated position.

The relay 4 does not budge, no modification having occurred in its supply circuit.

The winding 2 of the relay 3 is energized during the duration of the short pulse, which causes its armature to move to -T, and a negative polarity is applied to the terminal S.

20 milliseconds:

It is the theoretical instant of the beginning of the first characteristic element, but no modification of the received current is yet produced because of the delay of the distortion.

1. *The polarity of the first characteristic signal is negative*

(24 milliseconds for example, supposing a delay of distortion of 4 milliseconds).—The first characteristic element is effectively received at E:

The relay 1 continues to be excited by its winding 1 and remains in operated position. No change is produced for the relay 2, which remains in rest position. The relay 4 does not budge and the relay 3 continues to send to terminal S a negative polarity.

30 milliseconds.—Midpoint of the first characteristic element:

The winding 1 of the relay 1 continues to be energized, and the relay 1 remains in operated position.

The winding 2 of the relay 1 is not energized since the tube L2 does not oscillate, the frequency of its oscillations being equal to 120 milliseconds.

The winding 3 of the relay 2 is not energized for the same reason and the relay 2 remains in unenergized position as during the starting operation.

The tube L1 produces its second short pulse, the frequency of its oscillation being adjusted to 20 milliseconds. The relay 4 is energized in the same sense as during the starting period and does not budge.

The winding 2 of the relay 3 is energized during the duration of the short pulse produced by the tube L1 which retains relay 3 in its position -T.

A negative polarity continues to be sent to terminal B.

2. *The polarity of the first characteristic signal is positive*

(24 milliseconds for example, assuming a delay of distortion of 4 milliseconds).—The first characteristic element is effectively received at E:

The winding 1 of the relay 1 ceases to be energized, its winding 2 is no longer energized, and the relay 1 remains in operative position.

The armature of the relay 4 swings onto its other contact putting into circuit the winding 1 of relay 3, but this winding is not again energized, since there does not still exist the instant of the duration of the short pulse of the tube L1.

The armature of relay 3, therefore, stays on the contact -T and a negative polarity is always applied to the terminal S.

30 milliseconds.—Midpoint of the first characteristic element:

The windings 1 and 2 of the relay 1 are not energized, the relay 1 remains in operated position, the relay 2 remains in unenergized position, no modification occurring in its supply circuit.

The tube L1 produces a second short pulse during the period in which the winding 1 of the relay 3 is energized, the relay 4 remaining in

the same position. The armature relay 3 swings, sending a positive polarity to terminal S.

20 milliseconds.—Theoretical time of the beginning of the stop signal:

(126 milliseconds for example, supposing that the distortion delay is 6 milliseconds).—Beginning of the stop signal:

The polarity at the input becomes positive, the winding 1 of the relay 1 continues to not be, or ceases to be, energized, according to the polarity of the preceding signal, but the relay 1 at all events remains in energized position.

The relay 4 puts or maintains in a circuit the winding 1 of the relay 3, but this winding is not energized, since the oscillator tube L1 is not oscillating, so that the armature of the relay 3 stays in the position in which it was before.

130 milliseconds.—The tubes L1 and L2 each produce a pulse:

Across the tube L2 the winding 2 of relay 1 and the winding 3 of relay 2 are energized during the duration of the short pulse.

The winding 3 of the relay 2 puts the relay 2 into operated position since the winding 2 of this relay is at that time traversed by a positive current which, likewise, tends to place the armature in operated position; the two windings 2 and 3 act in the same sense and their action involves that of the winding 1; the energization of the winding 1 of relay 1 being interrupted, this relay immediately goes back to unenergized position because of the effect of its winding 2, the other contacts of relay 2 short circuit the shunted condensers R2C2 and R3C3.

Furthermore, the winding 1 of relay 3 is energized during the duration of the short pulse of the tube L1 and the armature of 3 passes, or remains, on the positive terminal, applying a positive polarity to the terminal S.

At the end of the short pulse, the winding 3 of relay 2 ceases to be energized and relay 2 returns to the rest position under the action of its winding 1 which is preponderant with relation to the winding 2.

The winding 2 of the relay 1 likewise ceases to be energized, the relay 1 does not budge and remains in rest position.

The relay 4 remains energized in the sense which corresponds to putting into circuit of the winding 1 of relay 3.

All the members are then restored to their initial state.

The device just described by way of example is intended to operate with a given particular code and a given defined duration of signals. It is obvious that without departing from the scope of the present invention, such a device would permit of correcting an arrhythmic telegraphic operation of any speed and code.

I claim:

1. A signal correcting device for a start-stop telegraph system comprising two input terminals to which are applied the distorted transmitted signal impulses which are to be regenerated, a source of continuous current, a first telegraph relay, a second double winding relay, said first relay being connected to be actuated by said received impulses, said second relay having two controlled contacts, said first relay being connected to connect with one pole of said source of continuous current, one terminal selectively of either one of the two opposing windings of said second relay according to the polarity of the received impulses which are applied to the

winding of said first relay, a pair of output terminals, said second relay being connected to apply to one of the said output terminals a positive or negative voltage according to the position of its armature, a relaxation oscillator tube arranged to produce spaced short pulses of the predetermined assigned duration of a signal element of the code being used, the other terminal in common of the two windings of said second relay being connected to the other pole of said source of continuous current through the output and input terminals of said tube.

2. A device according to claim 1, characterized by the fact that for the purpose of causing the triggering of the first pulse of the relaxation oscillator tube at the midpoint of the theoretical duration of the start signal element of each code character, it comprises a third starting relay, a rectifier connected to allow to pass only the currents whose polarity corresponds to the start signal element, one of the windings of said third relay being connected to the signal input terminals through said rectifier, the third relay being connected for closing the cathode circuit of said relaxation oscillator tube, the said third relay being retarded by an interval equal to half of the theoretical duration of a signal element of the code employed.

3. A signal correcting device for a start-stop telegraph system comprising two input terminals to which are applied the distorted transmitted signal impulses which are to be regenerated, a source of continuous current, a first telegraph relay, a second double winding relay, said first relay being connected to be actuated by said received impulses, said second relay having two controlled contacts, said first relay being connected to connect with one pole of said source of continuous current, one terminal selectively of either one of the two opposing windings of said second relay according to the polarity of the received impulses which are applied to the winding of said first relay, a pair of output terminals, said second relay being connected to apply to one of the said output terminals a positive or negative voltage according to the position of its armature, a relaxation oscillator tube arranged to produce spaced short pulses of the predetermined assigned duration of a signal element of the code being used, the other terminal in common of the two windings of said second relay being connected to the other pole of said source of continuous current through the output and input terminals of said tube, said device further comprising a second tube arranged as a relaxation oscillator and adjusted in such manner as to give spaced short pulses of the theoretical duration in the code employed of a complete character, a third starting relay having two windings, a fourth terminal relay, a plurality of condensers arranged for providing delay of the starting relay and the starting into oscillation of said second tube, the plate circuit of the said second tube being connected to energize on the one hand a second winding of said third starting relay which produces a flux opposed to that due to its first winding, and also being connected to energize a winding of said fourth terminal relay, said fourth terminal relay being connected to short circuit the said condensers.

4. A device according to claim 3, characterized by the fact that for the purpose of causing the initiation of the first pulse of said second relaxation oscillator tube at the same instant as that of the said first relaxation oscillator tube,

the cathode circuit of said second relaxation oscillator tube is closed through the same said third relay which also controls the cathode circuit of said first relaxation oscillator tube.

5. A device according to claim 3, characterized by the fact that for the purpose of avoiding having the first pulse of the second relaxation oscillator tube cause the operation of said fourth terminal relay, the said fourth relay comprises, besides its winding traversed by the output current of the said second oscillator tube, two other windings, one of which is connected to be permanently energized by a source of continuous current and the other winding of which is connected to be energized by the impulses of the received signal element received on said input terminals, the ampere-turns in each one of these three last said windings of said fourth relay being designed in such manner that the flux of the winding traversed by the output current of said 10 15 20 second tube can only cause the operation of said

fourth relay when its said winding which is energized by the impulses of the signals received on said input terminals is traversed by a current of the sense corresponding to that of the stop signal, and that the flux of said last mentioned winding can cause the operation of said fourth relay whatever may be the sense of the impulse of the received signal current.
